UNITED STATES PATENT OFFICE.

WALTER F. TROTTER, OF CHARLESTON, WEST VIRGINIA, ASSIGNOR, BY MESNE ASSIGNMENTS, TO THE JEFFREY MANUFACTURING COMPANY, A CORPORATION OF OHIO.

MINING-MACHINE.

1,127,700.

Specification of Letters Patent.

Patented Feb. 9, 1915.

Application filed September 20, 1906, Serial No. 335,453. Renewed March 16, 1912. Serial No. 684,224.

To all whom it may concern:

Be it known that I, WALTER F. TROTTER, a citizen of the United States, residing at Charleston, in the county of Kanawha and State of West Virginia, have invented certain new and useful Improvements in Mining-Machines, of which the following is a specification, reference being had therein to the accompanying drawing.

10 This invention relates to improvements in mining machines, particularly to side cutting mining machines. It has been proposed heretofore to provide machines of this class with flexible draft devices adapted to propel the machine along the face of the coal and to guide it or hold it to its work. In some cases cables were to be used as the flexible draft and holding members, and in other cases the functions of propelling and guiding the machine were to be performed by chains in connection with sprocket mechanisms or the like on the machines adapted to engage positively and rigidly with the chains. In one form of these latter machines, for example, 25 a single continuous chain is provided having one end fixed to an anchor or the like in advance of the machine and its other end fixed to an anchoring device on the rear side of the machine, while intermediate its ends the chain passes over sprocket drive mechanisms on the machine.

My invention, in its preferred form, contemplates the use of cables for propelling and guiding the machine and is intended to 35 provide a machine in which are overcome certain disadvantages and difficulties that have heretofore been experienced in the use of side cutting machines, especially in room and pillar mining.

40 The nature and all of the various objects of the invention will be understood in detail from the following description in connection with the drawings.

Figure 1 is a plan view of a mining machine embodying my improvements. Fig. 2 is a section on the line 2--2, Fig. 1. Fig. 3 is a side elevation of the same, a part of the cutter frame being broken away. Figs. 4 and 4¹ are sections on the line 4--4, Fig. 1.

50 Fig. 5 is a section on the line 5--5, Fig. 4. Fig. 6 is a section on the line 6--6, Fig. 4. Fig. 7 is a plan view of the inner portion of the cutter carrier and the guiding mecha-

nism for feeding it transversely to the coal face. Fig. 8 is a section on the line 8--8, 55 Fig. 7, the adjustable jack being removed. Fig. 9 is a view partly in elevation and partly in section of the jack stand and jack. Fig. 10 is a plan view showing the mining machine arranged to feed transversely to 60 the coal face at the beginning of a cut. Fig. 11 is a plan view showing the mining machine and its operating parts arranged to feed laterally along the coal face.

For the purpose of illustration I have 65 shown in the drawing a mining machine of which A indicates the main frame as an entirety, B the cutting apparatus extending from the inner end thereof and supported thereby, C the feeding and guiding mechanism for advancing the cutting apparatus and machine either longitudinally or laterally, D the motor mechanism, and E the auxiliary parts employed when it is desired to have the cutting apparatus advanced into 70 the coal transversely to the face thereof.

The main frame may be of any suitable construction as far as some features of my invention are concerned, but, for reasons which will later appear, I prefer a construction of the character shown. This construction comprises a plate-like shoe 1 adapted to rest upon the ground and slide freely in all directions, longitudinally arranged angle bars or plates 2, 2 secured to said shoe at 80 either side thereof and a suitable platform 3 resting upon and secured to said longitudinal side bars.

4, 4 are webs or plates depending from the platform 3 and carrying at their lower 90 ends the laterally turned longitudinally extending cutting apparatus guides 5, 5.

The main frame thus constructed constitutes a box which is closed on all sides except the inner and outer ends. It will be observed on reference to Figs. 3 and 4 that the platform 3 extends at its outer end beyond the bottom plate or shoe 1 and that the side plates 2 are correspondingly cut away. In other words, the outer end of the upper platform part of the main frame overhangs considerably.

The cutting apparatus comprises a longitudinally arranged horizontally disposed base plate 6, two longitudinally arranged 100 horizontally disposed guide plates, 7, above

said base plate and spaced therefrom by the longitudinally arranged bars 8 so as to form a chain guide or recess 9, the parts just referred to being secured together in any suitable manner, as by rivets 10.

11 is an inner sprocket wheel mounted upon a vertical axle 11', and between the inner end of the base plate 6 and a top plate 12 suitably secured to the base plate and having an outwardly extending centrally arranged part 12' fitted snugly between the top bars 7, 7 of the chain frame.

The motor D is suitably secured upon the platform 3 with its armature shaft 13 arranged longitudinally of the machine.

14 is a longitudinally arranged shaft, preferably having its axis in the vertical longitudinal plane of the axis of the chain frame. It is suitably mounted at either end in bearings 14', 14', one of which is carried by a bearing standard 14^a suitably secured to the platform 3. The inner standard 14^a extends transversely of the machine in either direction from the shaft 14 for the purpose to be hereinafter described.

15 is a spur gear rigidly secured to the shaft 14 and meshing with a pinion 16 secured to the inner end of the armature shaft 13.

17 is a bevel pinion loosely mounted on the shaft 14 near the outer end thereof.

18 indicates a positive clutch interposed between the said shaft 14 and the bevel pinion 17, the longitudinally stationary element 18' of said clutch being secured to the said bevel pinion and the longitudinally movable element 18^a being applied to the shaft.

18^b indicates suitable mechanism for moving the element 18^a of the clutch in either direction.

19 is a vertically disposed shaft suitably mounted in bearings carried by the main frame of the machine and having its axis in the vertical plane containing the axis of the shaft 14. 20 is a bevel gear secured to the upper end of the said vertical shaft and in mesh with the bevel pinion 17.

21 is a sprocket drive wheel rigidly secured to the lower end of the vertical shaft 19.

22 indicates as an entirety an endless cutter chain or carrier extending around the sprocket drive wheel 21 and the inner sprocket 11 carried by the cutter frame, it being arranged at either side within the guides 9 of the said cutter frame and carrying laterally extending cutters 23 of any suitable construction. The cutter frame is supported from the main frame by the longitudinally arranged slides or guides 5 depending from the main frame and arranged to fit snugly between the base plate and the upper plate of the chain frame. The main frame and the chain frame are normally held from longitudinal movement

relative to each other by mechanism indicated as an entirety by 24, which also serves as an adjusting means for moving the frames relative to each other to vary the tension upon the cutter chain. The adjusting mechanism 24 comprises a longitudinally arranged screw-threaded shaft 24' mounted near its inner end in a bearing in a depending plate 25 which is secured to the inner end of the main frame platform 3. Near its outer end it is fitted into a threaded nut 26 which is arranged between uprights or projections 27, 27' carried by the base plate 6. The inner end of this shaft is squared as indicated at 24^b to receive a suitable wrench for turning the shaft in either direction so as to extend the chain frame relative to the main frame or to force it in the opposite direction relatively thereto, as desired.

28 is a worm gear rigidly secured to the longitudinally arranged shaft 14 near the inner end thereof and between the bearing standard 14^a and the gear wheel 15 secured to the said shaft. 29 is a shaft arranged beneath the said shaft 14 and transversely of the main frame. It is suitably mounted in a bearing 29' secured to the platform of the said frame. 30 is a worm wheel secured to the inside end of the said transverse shaft 29 and in mesh with the worm 28 on the shaft 14.

31 is a worm rigidly secured to the outside end of the shaft 29.

32 is a longitudinally arranged shaft 100 mounted near either end of the bearings 32', 32', carried by bearing standards 14^a and 32^a, the latter being arranged parallel to the former and of substantially the same width and secured to the platform of the main frame. The axis of this shaft 32 is in a vertical longitudinal plane on the opposite side of the vertical longitudinal plane of the axis of the shaft 14 from armature shaft 13.

33 is a worm wheel rigidly secured to the outer end of the shaft 32 and in mesh with the worm 31 on the transverse shaft 29.

34 is a spur gear loosely mounted upon the shaft 32 adjacent to the bearing standard 14^a, and 35 is a gear wheel of greater diameter than the gear wheel 34 and loosely mounted upon the said shaft 32 adjacent to the bearing standard 32^a.

36 indicates as an entirety clutch mechanism for alternately connecting the gears 34 and 35 to the shaft 32. Of this clutch mechanism 36' indicates a longitudinally movable element splined to the shaft 32 and carrying at one end clutch jaws 36^a secured to the gear wheel 35 and at its other end clutch jaws 36^b adapted to engage with the clutch jaws 36^c carried by the gear wheel 34.

37 indicates as an entirety suitable mech-

anism for shifting the movable element 36 of the clutch in either direction at will. 38 is a longitudinally arranged drum shaft suitably mounted near either end in 5 bearings 38', 38", in the bearing standards 14^a and 32^a respectively. The axis of this shaft is on the opposite side of the vertical plane containing the axis of the shaft 14 from the axis of the shaft 32.

10 39 is a gear wheel rigidly secured to the shaft 38 near one end thereof and in mesh with the gear wheel 34 on the shaft 32, and 40 is a gear wheel of smaller diameter than the gear wheel 39 and rigidly secured near 15 the opposite end of the shaft 38 and in mesh with the gear wheel 35 on the shaft 32.

20 41 is a cable winding drum loosely mounted on the shaft 38 and preferably adjacent to the gear wheel 40 at the inner end thereof. The periphery of the cable drum may be spirally grooved as indicated at 41' to assist in the spooling upon it of a draft cable which has one end suitably fastened to said drum. The drum is preferably connected to the shaft 38 by means of a friction clutch 41^a, one element of which is a ring or casing 41^b carried by the drum and extending outwardly therefrom, and the other element of which is a pulley or ring 30 41^c having its rim radially slotted at 41^d, 41^e, as indicated. 41^e are adjustable wedges or expanders arranged between the sections of the rim at said slots and adapted to force the periphery of the rim into engagement 35 with the inner walls of the ring 41^b in the well known manner. By varying the adjustment of the expanders the clutch can be made to slip when the resistance to the rotation of the winding drum reaches any given 40 amount.

42 is a bearing bracket secured to the side plate 2 adjacent to the drum 41. 42' is a longitudinally arranged shaft suitably supported by the laterally extending arm 42^a 45 of the said bracket.

43 is a vertically disposed idler pulley on the shaft 42'.

44 is a horizontally disposed idler guide wheel on a vertically arranged shaft 44' 50 suitably mounted near the inner end of the main frame on the opposite side thereof from the idler pulley 43.

45 is a swingable arm pivotally mounted at its inner end to the platform of the main frame on a vertical pivot 45'. At its outer end it is offset vertically as indicated at 45^a to receive a horizontally disposed idler guide 46 mounted on a vertically arranged pivot 46' which connects the front end of 55 the arm 45^a with the front end of a bar or plate 47, the rear end of which is rigidly secured by screws 47', 47", to the arm 45.

48 is an adjusting shaft or rod for the swingable arm 45, having its inner end connected to the said arm by a universal joint

48'. The outer end of the adjusting rod 48 is screw threaded as indicated at 48^a and fitted into a screw threaded nut 49 which is pivotally connected at 49' to the platform of the main frame. The extreme outer end 70 of the rod 48 is squared as indicated at 48^b to receive a wrench for imparting rotary movement to said shaft in either direction.

50 is a suitable draft and guide cable having one end rigidly secured on the cable-winding drum 41. When the machine is undercutting along the face of the coal this cable extends from the top of said drum downward around the idler guide 43 and then forward as indicated at 50' and around a horizontally disposed idler guide wheel 51 pivotally mounted in a jack 52 suitably secured in position adjacent to the coal face at the end of the cut to be made. From the 85 said idler guide wheel 51 the cable is carried rearwardly, as indicated at 50^a, closely adjacent to the coal face and along the inner end of the main frame of the mining machine, thence around the idler guides 44 and 46 thereon, as indicated at 50^b and then rearward again, as indicated at 50^c, and has its rear end secured to a rear jack 53, suitably held in position near the coal face. With the cable thus arranged, rotation of 95 the drum 41, by creating tension in the cable, causes the machine to be advanced along the face, the cutters simultaneously undercutting the coal. During such operation the cable serves also, in a manner which will 100 later be described, to guide the machine and maintain it in suitable working relation to the coal face.

In longwall mining an undercut is usually easily started at a free face, but in room 105 and pillar work an entering or "sumping" cut must be made in order to get the cutting apparatus under the coal, this entering cut being made adjacent one or the other of the ribs constituting the side walls of the room. With my improved machine the sumping cut is made by feeding the machine bodily longitudinally forward so as to project the cutting apparatus into the coal. The side cutting machines heretofore proposed for 110 room and pillar work have been open to serious objection in connection with the making of the sumping cut. Either there was no adequate provision for effecting the sumping cut or, in the case of other machines, this entering cut could be effected only by the use of a large, heavy and cumbersome pan or frame designed to support 115 the entire machine and guide it while it was forced endwise toward the coal face in much the same manner as the main frame of a "breast" machine supports and guides its cutter frame and carriage. It is my purpose to do away with the heavy and cumbersome supporting frame and I have, accord- 120 125 130

ingly, designed the main frame of my machine to work directly on the floor of the mine, and have provided light and easily handled guide devices that operate to prevent the swinging of the machine while it is slid endwise on the mine floor to initially advance the cutters under the coal. These guide devices of my machine are the combined jack and cutter mechanism guide E 10 illustrated in Figs. 7, 8, 9 and 10. 54 is a base plate of the said jack stand adapted to rest upon the floor of the mine closely adjacent to the coal face and at an angle thereto, as shown. Near either end of this base plate 15 is a pair of upwardly extending arms or lugs 55 supporting between them a shaft or pivot 56 with its axis arranged longitudinally of the base plate.

57 indicates the jack proper comprising a shank or bar 57' forked at its lower end as indicated at 57^a, the ends of each arm of said fork being recessed as indicated at 57^b to fit over one of the shafts 56 on the base plate. The upper end of the jack shank is screw 25 threaded at 57^c to receive a screw threaded hand adjusting wheel 58.

59 is a pointed head for the jack swiveled on the upper end of the jack 57' and bearing against the upper face of the hub of the 30 wheel 58 by means of which it is adjusted longitudinally of the shank.

54' is an arm or plate extending laterally from the base plate 54 and carrying the upright bracket 54^a which at its upper end is 35 bifurcated as indicated at 54^b to receive one end of a swinging arm 60, which is pivotally connected to the upright 54^a by means of a bolt 60'. At its free end the arm 60 has pivotally connected to and depending from 40 it a slide 61 which is longitudinally grooved at either side to receive the adjacent longitudinal guide bars 12^b on the chain frame. These guide bars 12^b are rigidly secured in position by means of bolts 12^c screw-threaded into inwardly projecting lugs 12^d carried 45 by the base plate 6 of the chain frame. The slide 61 may be introduced into position within the said top plate at the ends of the guides 12^b adjacent the main frame. The 50 slideable connection between the slide 61 and the cutter frame permits the longitudinal movement of the cutter frame relative to the slide while tending to prevent the lateral movement in either direction of the cutter 55 frame relative to the base plate 54. It will thus be seen that when the jack stand is securely fastened in position by means of the jack 57, the cutter frame may be caused to travel forward in a substantially straight line. When the slide 61 reaches the ends of 60 its guides 12^b it may be swung upwardly out of the path of travel of the cutter frame.

To operate the machine for room and pillar work it is unloaded at the corner of the 65 room where it is desired to begin the cut

and with the end of the cutter frame closely adjacent to the face of the coal. The combined jack and cutter frame guide E is then clamped securely in position on the left hand side of the cutter frame near the end 70 thereof, as indicated in Fig. 10, the slide 61 having been introduced into its guide in the top plate of the said frame. The cable 50 is next carried inward from the drum 41 along the side of the machine to the inner end of 75 the jack frame and pivotally connected thereto, as indicated at 62, a suitable idler guide 63 serving to direct the course of the cable from the drum toward the said jack stand. This idler guide 63 is mounted on a journal 64 carried by a U-shaped bracket 65 which is pivotally mounted on a longitudinal shaft 66 carried by lugs 67, 67, projecting laterally from the main frame. The U-shaped bracket 65 has a laterally extending lug or projection 65' which is adapted to engage with the platform of the main frame to limit the inward travel of the bracket 65 about the axis of the shaft 66, as indicated in Fig. 6. The bracket 65 may be readily 90 detached by removing the shaft 66, whenever it is not desired to use the idler guide 63.

The motor having been started, the cutting apparatus and the slow-feed gearing of 95 the winding drum are then connected to the motor by clutches 18 and 36 respectively. The drum 41 winds up on the cable and pulls the main frame of the machine toward the coal face, the cutting apparatus simultaneously undercutting the coal. The cutter frame guiding mechanism tends to insure 100 that the cutting apparatus will be moved inward in a substantially straight line. When the slide 61 reaches the ends of the guides 12^b it is withdrawn therefrom and the machine will feed inward without further guiding. The sumping cut having been completed, the machine is stopped, the guide jack E and the idler guide 63 moved, and the cable 50 extended to the far rib and around the fixed guide sheave 51, thence back to the machine where it is passed around guides 44 and 46 and thence rearward to the jack 53. See Fig. 11. The motor is now started and 110 clutches 18 and 36 closed so as to drive the cutters and the winding drum 41. Ordinarily the winding drum is driven through the low speed gearing when the cutters are at work, the high speed gearing being used 115 when the propelling cable is employed simply to move the machine about in the room. The rotation of the winding drum 41 creates tension in the cable 50 tending to advance the machine along the face of the coal. 120 Under the action of this forward draft, the outer end of the machine tends to swing forward relative to the cutter frame because of the resistance which the coal offers to the 125 advance of the cutters. This tendency, how- 130

ever, is overcome and the machine is maintained in proper working position relative to the face of the coal by the rear cable section 50° which draws between the guide 5 wheel or sheave 46 and the jack 53 and thus exerts a retarding draft on the outer part of the machine.

It will be observed that the machine as an entirety is subjected to the action of three 10 main forces, viz., the rearward reaction of the coal on the cutter frame, the forward draft of the cable sections 50' and 50^a on the inner end of the main frame, and the rearward draft of the cable section 50^c on the 15 outer part of the main frame. Under the action of these forces the machine tends, when the forces are not balanced, to swing about a point at the inner end of the frame at which the resultant draft of cable sections 20 50' and 50^a is applied. As the machine advances along the face of the coal the cable section 50' is wound up on drum 41, while the cable sections 50^a and 50^c remain extended along the face and serve as a guide to 25 hold the machine up to its work, the rear section 50^c exerting a rearward draft on the outer part of the machine which prevents the outer end of the machine from advancing more rapidly than the inner end. Thus, 30 it will be seen, the propelling and guiding mechanism is adapted to maintain the machine at a given angle to the face as the undercut proceeds. At the same time, it is possible to readily change the angle of the 35 machine to the face of the coal whenever this is desirable because of the varying character of the material being cut, the conformation of the mine floor or the coal face, etc., for example, in case the cutters encounter 40 a streak of harder coal or of hard impurities in the coal, it may be desirable to angle the cutter bar forward and maintain the machine thus inclined while cutting through such streak. Any such swinging of 45 the machine can readily be effected as the machine advances by simply turning the screw 48, so as to swing the arm 45. To angle the cutter frame forward the arm 45 is swung outward. This acts to shorten the 50 cable section 50^c and to cause a corresponding relative rearward movement of the outer end of the machine. Such an adjustment of the arm 45 also increases the leverage with 55 which the draft of the retarding cable acts on the machine because it moves the guide sheave 46 nearer the outer end of the machine and carries the line of draft of the cable section 50^c farther from the guide sheave 43 about which the machine tends to 60 swing. Obviously such an increased leverage is advantageous when the cutters are encountering an increased resistance. If the arm 45 is swung inward it is clear that the cable section 50^c will be lengthened, allowing the outer end of the machine to

swing forward, and that the leverage with which the retarding draft of said cable section is applied to the machine will be decreased.

While, in the construction illustrated, the means for angling the machine presents both of the above effects, viz., the variation in the effective length of the rear cable section and the variation in the leverage of said cable section on the machine, it will be understood that there is no essential relation between the two effects, it being obviously possible to vary the effective length of the rear cable section without varying its leverage on the machine. In any case, however, the angling of the machine is found to be characterized by variation, relative to the machine, of the lines along which the cable stresses are exerted on it.

When it is desirable to do so, the swinging movement of the machine can be effected periodically first in one direction, then in the other, so that the machine is given an oscillatory movement as it advances along the face. Such a handling of the machine 25 is sometimes advantageous when the coal carries impurities in the form of hard nodules, since the oscillatory movement, by changing the line of attack of the cutters, tends to loosen such impurities.

I have referred above to the propelling and guiding mechanism as adapted to maintain the machine at a given angle to the face. Under some conditions, however, as for example, when impurities of great 100 density and hardness are encountered by the cutters, it is desirable that the machine have greater flexibility in its movement. When the cutters meet abnormally great resistance, there is danger of breakage of some 105 part or parts of the machine if the mechanism is such that an unvarying movement of the machine is necessary regardless of the resistance encountered. In the case of my improved machine the propelling reel 41 is 110 driven from the motor through the friction clutch 41^a which can be set to slip when the tension in the draft cable 50 reaches any amount determined upon. Therefore, when the cutters encounter an abnormally high 115 resistance due to hard impurities or the like, such increased resistance, if sufficiently great, will result in slippage between the parts of the friction clutch 41^a so that the winding reel 41 is driven at a slower speed. 120 Thus, the advance of the machine is retarded and the cutters are given an opportunity to cut through the harder material.

In all of the advancing and swinging movements of the machine it is free to slide 125 in any direction over the floor of the mine, and in usual practice, if the mine floor is soft or uneven, this free movement of the machine is facilitated by the use of flat skids such as have been known and used for many 130

years in the moving and adjusting of mining machines both of the "breast-machine" class and of the "long-wall" class. These skids, which are in the form of thin metal plates a few inches wide, are laid upon the floor of the mine in the direction of the machine's advance and, by affording a hard smooth surface for the main frame, greatly facilitate the movement of the machine.

10 It will be understood that the friction clutch 41^a can be set to give way under any stress within a reasonable range so that the machine can be made to cut through minor impurities or hard streaks without slippage

15 occurring. In some deposits of coal, impurities are encountered which are of such great density and hardness or so extensive that it is not desirable to attempt to cut through them. In some such cases it is pos-

20 sible to carry the undercut over or under the obstruction, in the manner which has been commonly followed heretofore in the using of side cutting mining machines, and my improved machine is well adapted to work

25 under such conditions. Thus, if a roll is encountered, it may be found possible to back the machine off along the face to a suitable distance from the obstruction and then by blocking up the skids, which, as previously noted are commonly used with such machines, the cutters may be guided in an upwardly inclined path over the obstruction and then gradually downward again to the normal level.

35 Reference has already been made to the box-like construction of the main frame of the machine. This I regard as a feature of much practical importance. During the cutting operation the fine coal or slack

40 which is formed is dragged out of the kerf by the cutters and must be handled or disposed of in such a way as not to clog or interfere with the cutters or other working parts of the machine. In my improved con-

45 struction this fine coal is drawn into and outward through the box-like main frame to the outer end of the machine by the cutters. There as the cutter chain rounds the driving sprocket wheel, the fine material

50 falls either quite clear of the machine as it advances, or, if it is not delivered entirely clear of the machine, it is possible for the machine runner or his helper to readily shovel it away because the cutting away of

55 the side plates of the frame at the outer end thereof leaves a free space adjacent the driving sprocket wheel and beneath the upper platform part of the frame which permits ready and effective use of the shovel

60 for the purpose stated. Furthermore, it will be observed that with the exception of the cutters and the sprocket wheel which drives them, all of the working parts—gears, winding drum, clutches, motor, etc.—are mounted

65 above the upper platform part of the frame

so as to be fully protected from contamination with the fine coal or slack which cannot rise and enter any of these working parts during its passage from the face outward to the point where it is delivered by the cutters 70 free of the machine. In this connection it will be observed that practically all of the gears, shafts and clutches constituting the driving mechanism are grouped compactly together on one part of the frame platform 75 while the motor occupies another part. This arrangement of the motor and the driving gearing greatly facilitates the complete protection of the gearing from dust because it makes it possible to inclose the gearing by 80 means of a simple protecting casing.

In the foregoing description of the operation of the machine its use in room and pillar mining was considered, it will be obvious without further detailed description 85 that the operation in making an under-cut along the face would be essentially the same in longwall mining. Ordinarily in longwall mining it is not necessary to make an entering or sumping cut because the cut can 90 be started at a free face.

Referring to Figs. 1, 2 and 5, have shown means by which power may be transmitted to gearing on a suitable mining machine truck upon which the mining machine 95 may be mounted, said gearing being for the purpose of propelling the truck. This mechanism comprises a transversely arranged shaft 68 in axial alinement with the transverse shaft 29, the inside end of which 100 latter shaft is fitted into a recess 68' in the inside end of the shaft 68. 69 is a positive clutch one element of which 69' is secured to the shaft 29 and the other element 69^a is carried by the inside end of the shaft 68. 105 The shaft 68 is suitably supported on a gearing 70 secured to the main frame. 71 is a sprocket wheel rigidly secured to the outside end of the shaft 68 and adapted to be connected with the propelling mechanism 110 on the mining machine truck. When not required in use the shaft 68 may be removed from the machine by drawing it longitudinally out from the bearing 70.

When the machine is to be moved from 115 place to place in the mine, the cable 50 is wound up on reel 41 so that the machine is reduced to a compact form which can be conveniently handled and moved about. In the case of prior machines in which loose 120 ended chains or cables are employed, great inconvenience has been experienced in handling the machines when they were to be moved about in the mine, but in the case of my machine this inconvenience is obviated. 125

While, in the preferred form of construction which I have shown and described, the forward or propelling section of cable and the rearward or retarding section of cable form parts of a single continuous cable, it is 130

to be understood that my invention in respect to some of its features, and especially in respect to the means for varying the respective lines of draft on the inner and outer parts of the main frame of the machine, is not limited to the use of a continuous cable, nor even to the use of a cable system in which the forward draft section and the rearward draft section are operatively connected. In other words, I believe myself to be the first to provide a machine of the class in question having any kind of a propelling and guiding cable system presenting a section of cable arranged to exert a forward draft on the inner part of the main frame of the machine, and a section of cable arranged to exert a rearward draft on the outer part of the main frame, together with means, mounted on the machine, for varying with relation to the machine the lines along which the drafts of said sections of cable are exerted thereon. Furthermore, while I have shown and prefer to use cable as the flexible draft means of my machine, I do not thereby intend to limit the scope of my invention to the use of cable where the advantages of my improvements can be realized in some degree by the use of other known flexible draft means. And while I have shown and described a particular form of winding drum for the cable, such disclosure is to be taken as merely illustrative and the terms "winding drum" and "winding device" are to be understood as standing for any suitable device for creating in the cable a tension adapted to propel the machine over the mine floor.

What I claim is:

- 40 1. In a mining machine of the class described, the combination with the main frame, cutting apparatus projecting inward therefrom, the motor and the gearing thereon all adapted for undercutting coal while moving on lines along the face of the coal, of a feed and guide mechanism comprising a cable-winding device on the frame, a cable system having a forward extending section connected with the cable-winding device and adapted to coöperate with anchoring means in front of the machine to exert a forward pulling stress on the main frame at a point near the inner end thereof and a rearward extending section adapted to coöperate with anchoring means behind the machine to exert a rearward stress on the main frame at a point nearer the outer end thereof than the said point of forward stress thereon, and manually controllable devices on the main frame adapted to vary in relation to the machine the lines along which the cable stresses are exerted thereon.
- 45 2. In a mining machine of the class described, the combination with the main frame, the cutting apparatus projecting in-
- ward therefrom, the motor and gearing thereon, all adapted for undercutting coal while moving on lines along the face of the coal, of a feed and guide mechanism comprising a cable-winding device on the frame, 70 a cable system having a forward extending section connected with the said cable-winding device and adapted to coöperate with anchoring means in front of the machine to exert a forward draft on the main frame at a point near the inner end thereof and a rearward extending section adapted to coöperate with anchoring means behind the machine to exert a rearward draft on the main frame at a point nearer the outer end thereof than the said point of forward draft thereon, and means for adjusting the second, or outer point of draft inward and outward to vary the guiding action of the cable system. 75
3. In a mining machine of the class described, the combination of a main frame, cutting apparatus projecting from the inner end thereof, mechanism for feeding and guiding the machine along the face of the material to be cut, the said mechanism comprising a cable-winding device on the frame, a cable section engaging the winding device and arranged to extend forward to a suitable anchor in front of the machine, a 80 length of cable arranged to extend from such front anchor to a point of draft on the inner end of the main frame, thence outward to a second point of draft on said frame and thence rearward to a suitable 85 anchor behind the machine and means for adjusting the said second point of draft inward and outward to vary the guiding action of the mechanism. 90
4. In a mining machine, the combination 105 of a main frame, cutting apparatus projecting from the inner end thereof, and a mechanism for feeding and guiding the machine along the face of the material to be cut, said mechanism comprising a winding drum on the main frame, a cable attached to said drum and arranged to extend from the inner end of the machine to a suitable anchor in front of the machine, thence rearward to a point of draft on the inner end 110 of the main frame, thence outward to a second point of draft on said frame and thence rearward to a suitable anchor behind the machine, and means for adjusting the said second point of draft inward and outward 115 to vary the guiding action of the mechanism. 120
5. In a mining machine, the combination 125 of a main frame, a cutting apparatus projecting from the inner end thereof, a motor, a winding drum mounted on said frame, power transmitting mechanism interposed between said motor and said winding drum, a pair of idler guide wheels mounted upon vertical axes on said main frame, and ar- 130

ranged one nearer the inner end of said frame than the other, one of said idler guide wheels being adjustable toward and from the other one, a flexible draft device having one end secured to said winding drum and arranged to extend thence forward around a suitable anchor in front of the machine, then rearward and around the said idler guide wheels on the main frame and thence to a suitable anchor behind the machine, the tension on the said flexible draft device applied through the leverage on said frame provided by said idler guide wheels serving to hold the machine to its work.

6. In a mining machine, the combination of a main frame, a cutting apparatus projecting from the inner end thereof, a motor, a winding drum mounted on said frame, power transmitting mechanism interposed between said motor and said winding drum, a pair of idler guide wheels mounted upon vertical axes on the main frame and arranged one nearer the inner end of said frame than the other, the outer one of said idler guide wheels being adjustable toward and away from the inner one, a flexible draft device having one end secured to said winding drum and arranged to extend thence forward around a suitable anchor in front of the machine, thence rearward around said idler guide wheels on the main frame and thence rearward to a suitable rear anchor to which its rear end is secured, the tension on the flexible draft device applied through the leverage on said frame provided by said idler guide wheels serving to hold the machine to its work.

7. In a mining machine, the combination of a main frame, a cutting apparatus projecting from the inner end thereof, a motor, a winding drum mounted on said frame, power transmitting mechanism interposed between said motor and said winding drum, a pair of idler guide wheels mounted upon vertical axes on the main frame and arranged one nearer the inner end of said frame than the other, the outer one of said idler guide wheels being arranged to swing about a vertical axis toward or away from the inner one, a flexible draft device having one end secured to said winding drum and arranged to extend thence forward around a suitable anchor in front of the machine, thence rearward around said idler guide wheels on the main frame and thence rearward to a suitable rear anchor to which its rear end is secured, the tension on the flexible draft device applied through the leverage on said frame provided by said idler guide wheels serving to hold the machine to its work.

8. In a mining machine, the combination of a main frame, cutting apparatus projecting from the inner end thereof, and a mechanism for feeding and guiding the

machine along the face of the material to be cut, said mechanism comprising a horizontally arranged guide wheel on the inner end of the main frame, a horizontally swingable arm having one end pivoted in said frame and its other end disposed outward from the aforesaid guide wheel, a second horizontally arranged guide wheel on the free end of the swingable arm, means for swinging said arm and holding it in adjusted position, a winding drum on the main frame, a cable engaging said drum and arranged to extend forward therefrom to a suitable anchor in front of the machine, thence rearward to the inner guide wheel on the machine, thence to the outer guide wheel and thence to a suitable anchor behind the machine.

9. In a mining machine, the combination of a main frame, a cutting apparatus projecting from the inner end thereof, a motor, a winding drum mounted on the main frame near the inner end thereof, power transmitting mechanism interposed between said motor and said winding drum, an idler guide wheel mounted on a vertical axis on the rear side of the main frame near the inner end thereof, another idler guide wheel mounted on a vertical axis on the same side of the machine as the said first idler guide wheel and outward therefrom, and a flexible draft device having one end secured to said winding drum and being arranged to extend thence forward from said drum around a suitable anchor in front of the machine and then rearward and around the idler guide wheels on the rear side of the machine and thence rearward to a suitable rear anchor to which its rear end is secured.

10. In a mining machine, the combination of a main frame, a cutting apparatus projecting from the inner end thereof, a motor, a winding drum mounted on said frame near the inner end thereof, power transmitting mechanism interposed between said motor and said winding drum, an idler guide wheel mounted on a vertical axis on the rear side of the main frame near the inner end thereof, another idler guide wheel mounted on a vertical axis on the same side of the machine as the said first idler guide wheel and outward therefrom and adapted to be moved forward and back relatively thereto, and a flexible draft device having one end secured to said winding drum and arranged to extend forward from said drum around a suitable anchor in front of the machine and then rearward and around the idler guide wheels on the rear side of the machine and thence rearward to a suitable rear anchor to which its rear end is secured.

11. In a mining machine of the class described, the combination of a main frame, cutting apparatus projecting from the inner end thereof, and mechanism for feeding the

and guiding the machine along the material to be cut, said mechanism comprising a cable-winding device on the frame, a cable system having a forward extending section connected with the said cable-winding device and adapted to coöperate with anchoring means in front of the machine to exert a forward pulling stress on the main frame at a point near the inner end thereof and having a rearward extending section connected with the forward section and adapted to coöperate with anchoring means behind the machine to exert a rearward stress on the main frame at a point nearer the outer end thereof than the said point of forward stress thereon, and guide devices on the frame for the cable comprising an adjustable sheave adapted when adjusted to vary the length of the rearward extending cable section between its point of draft on the machine and the rear anchor.

12. In a mining machine of the class described, the combination of a main frame having a bottom part permanently, rigidly united to the other frame parts and adapted in operation to rest directly on and slide over the mine floor, a cutter frame rigid with the main frame and projecting from the inner end thereof, an endless cutter chain mounted on the cutter frame, propelling means adapted to bodily slide the machine endwise on the mine floor transversely to the coal face to initially advance the cutters under the coal, and guide devices operable, while the machine slides as aforesaid on the mine floor, to resist swinging of the machine in relation to the coal face.

13. In a mining machine of the class described, the combination of a main frame adapted to rest on the floor of the mine, a cutter frame rigid with the main frame and projecting from the inner end thereof, an endless cutter chain mounted on the cutter frame, propelling means adapted to bodily slide the machine endwise on the mine floor transversely to the coal face to initially advance the cutters under the coal, and means for guiding the machine in its endwise movement, said means being constructed to engage the cutter frame and being adapted to be fixed against movement on lines transverse to the cutter frame.

14. In a mining machine of the class described, the combination of a main frame, cutting apparatus comprising a cutter frame rigid with the main frame and projecting from the inner end thereof and a cutter chain mounted on the cutter frame, means for bodily propelling the machine transversely to the face of the material to be cut to initially advance the cutters under said material, and a guide device adapted to guide the cutting apparatus at the beginning of the undercutting, said device having one end adapted to be secured against

movement along the face of said material and its other end having a slideable connection with the said cutter frame.

15. In a mining machine of the class described, the combination of a main frame, cutting apparatus projecting from the inner end of the main frame, said apparatus comprising a cutter frame rigid with the main frame and formed with a longitudinally extending guide and a cutter chain mounted on the cutter frame, a slide fitted to the said guide of the cutter frame, and a slide carrying arm having one end connected to said slide and its other end arranged to be rigidly secured against movement along the face of the material to be cut so as to guide the cutting apparatus at the beginning of the undercutting, and means for bodily propelling the machine transversely to the face of the said material.

16. In a mining machine of the class described, the combination with a main frame, cutting apparatus comprising a cutter frame rigid with the main frame and projecting from the inner end thereof and a cutter chain mounted on the cutter frame, and means for bodily propelling the machine transversely to the face of the material to be cut to initially advance the cutters under said material, of a cutting apparatus guide arm having at one end a slideable connection with said cutting apparatus and at its other end means for clamping it against movement along the face of the said material so as to guide the cutting apparatus at the beginning of the undercutting.

17. In a mining machine of the class described, the combination with a main frame, cutting apparatus projecting from the inner end thereof, said apparatus comprising a cutter frame rigid with the main frame and a cutter chain mounted on the cutter frame, and means including a flexible draft device for propelling the machine bodily transversely to the face of the material to be cut, of a jack stand adapted to be clamped securely in position adjacent the said face, means for securing the free end of said draft device to the jack stand, and a guide arm for the cutting apparatus having one end mounted on said jack stand and its other end slidably connected with the cutter frame.

18. In a mining machine of the class described, the combination of a main frame, a cutting apparatus projecting from the inner end thereof, said apparatus comprising a cutter frame rigid with the main frame and a cutter chain mounted on the cutter frame, means for bodily propelling the machine transversely of the coal face to initially advance the cutters under the coal, and a guiding device for the cutting apparatus slidably connected with the cutter frame and adapted to be fixed against

movement transverse to the lines of the machine's advance.

19. In a mining machine of the class described, the combination of a main frame, a cutter frame rigid with the main frame and projecting from the inner end thereof, an endless cutter chain mounted on the cutter frame, means for bodily propelling the machine endwise transversely to the coal face to initially advance the cutters under the coal, and means adapted to be fixed against movement in a direction transverse to the cutter frame and to slidably engage therewith to guide the machine during the first part of the initial under-cutting.

20. In a mining machine of the class described, the combination of a main frame adapted to rest on the floor of the mine, a cutter frame rigid with the main frame and projecting from the inner end thereof, an endless cutter chain mounted on the cutter frame, propelling means adapted to bodily slide the machine endwise on the mine floor transversely to the coal face to initially advance the cutters under the coal, and guide devices operable, while the machine slides as aforesaid on the mine floor, to resist swinging of the machine in relation to the coal face.

21. In a mining machine of the class described, the combination of a main frame, cutting apparatus projecting from the inner end thereof, and mechanism for feeding and guiding the machine along the material to be cut, said mechanism comprising a cable-winding device on the frame, a cable system having a forward extending section connected with the said cable-winding device and adapted to coöperate with anchoring means in front of the machine to exert a forward pulling stress on the main frame at a point near the inner end thereof and having a rearward extending section connected with the forward section and adapted to coöperate with anchoring means behind the machine to exert a rearward stress on the main frame at a point nearer the outer end thereof than the said point of forward stress thereon, said cable system presenting a continuous length of cable arranged to extend from the front anchoring means across the machine to the rear anchoring means, inner and outer guides on the main frame with which the said continuous length of cable engages, and means on the machine adapted in coöperation with the cable and guides to swing the machine relative to the face of the coal.

22. In a mining machine, the combination of a main frame, a cutting apparatus projecting from the inner end thereof, cable guide devices mounted on the main frame, one of said guide devices being nearer the inner end of the machine than the other, a continuous cable engaging the guide devices on the machine and adapted to be extended forward to an anchor in front of the machine and rearward to an anchor behind the machine, a rotary means on the machine engaging the cable and adapted to create tension therein to advance the machine, and means mounted on said main frame for varying the length of that part of the cable between its point of rearward draft on the machine and the rear anchor to vary the angle of the machine to the coal face.

23. In a mining machine, the combination of a main frame, an endless chain cutting apparatus disposed longitudinally of the main frame and projecting from the inner end thereof, means for propelling the machine laterally along the face of the coal to be undercut comprising a winding drum mounted upon said frame to rotate on an axis longitudinal of the frame, a cable system having a forward extending section connected with the winding drum and adapted to coöperate with anchoring means in front of the machine to exert a forward stress on the inner part of the main frame and a rearward extending section adapted to coöperate with anchoring means behind the machine to exert a rearward stress on the outer part of the main frame, a guide sheave for the forward cable section mounted on the main frame adjacent the winding drum and below the axis thereof and which directs the cable downward whereby the cable is caused to exert a draft on the machine below the axis of the winding drum.

ble-winding device on the frame, a cable system having a forward extending section connected with the said cable-winding device and adapted to coöperate with anchoring means in front of the machine to exert a forward pulling stress on the main frame at a point near the inner end thereof and having a rearward extending section connected with the forward section and adapted to coöperate with anchoring means behind the machine to exert a rearward stress on the main frame at a point nearer the outer end thereof than the said point of forward stress thereon, said cable system presenting a continuous length of cable arranged to extend from the front anchoring means across the machine to the rear anchoring means, inner and outer guides on the main frame with which the said continuous length of cable engages, and means on the machine adapted in coöperation with the cable and guides to swing the machine relative to the face of the coal.

24. In a mining machine, the combination of a main frame, a cutting apparatus projecting from the inner end thereof, cable guide devices mounted on the main frame, one of said guide devices being nearer the inner end of the machine than the other, a continuous cable engaging the guide devices on the machine and adapted to be extended forward to an anchor in front of the machine and rearward to an anchor behind the machine, a rotary means on the machine engaging the cable and adapted to create tension therein to advance the machine, and means mounted on said main frame for varying the length of that part of the cable between its point of rearward draft on the machine and the rear anchor to vary the angle of the machine to the coal face.

25. In a mining machine, the combination of a main frame, an endless chain cutting apparatus disposed longitudinally of the main frame and projecting from the inner end thereof, means for propelling the machine laterally along the face of the coal to be undercut comprising a winding drum mounted upon said frame to rotate on an axis longitudinal of the frame, a cable system having a forward extending section connected with the winding drum and adapted to coöperate with anchoring means in front of the machine to exert a forward stress on the inner part of the main frame and a rearward extending section adapted to coöperate with anchoring means behind the machine to exert a rearward stress on the outer part of the main frame, a guide sheave for the forward cable section mounted on the main frame adjacent the winding drum and below the axis thereof and which directs the cable downward whereby the cable is caused to exert a draft on the machine below the axis of the winding drum.

25. In a mining machine of the class described, the combination with the main frame, cutting apparatus projecting inward therefrom, the motor and the gearing thereon all adapted for undercutting coal while moving on lines along the face of the coal, of a feed and guide mechanism comprising a cable-winding device on the frame, a cable system having a forward extending section connected with the cable-winding device and adapted to coöperate with anchoring means in front of the machine to exert a forward pulling stress on the main frame at a point near the inner end thereof and a rearward extending section adapted to coöperate with anchoring means behind the machine to exert a rearward stress on the main frame at a point nearer the outer end thereof than the said point of forward stress thereon, and means mounted on the main frame adapted in coöperation with the rear cable section to cause the inner end of the machine to swing forward and backward as the machine advances along the coal face.
- 10 26. In a mining machine of the class described, the combination with a main frame and cutting apparatus projecting inward therefrom, a motor and gearing thereon, all adapted for undercutting coal while moving along the face thereof, of a feed and guide mechanism comprising a cable-winding device on the frame, a cable system having a forward extending section connected with said cable-winding device and adapted to coöperate with anchoring means in front of the machine to exert a forward pulling stress on the main frame at a point near the inner end thereof and a rearward extending section adapted to coöperate with anchoring means behind the machine to exert a rearward stress on the main frame at a point nearer the outer end thereof than the said point of forward stress thereon, and means mounted on the main frame for varying the length of the rearward extending cable section between its point of draft on the machine and the rear anchor to vary the angle of the machine to the coal face.
- 15 27. In a mining machine of the class described, the combination with the main frame, cutting apparatus projecting inward therefrom, the motor and the gearing thereon all adapted for undercutting coal while moving along the face thereof, of a feed and guide mechanism comprising a cable-winding device on the frame, a cable system having a forward extending section connected with said cable-winding device and adapted to coöperate with anchoring means in front of the machine to exert a forward pulling stress on the main frame at a point near the inner end thereof and a rearward extending section adapted to coöperate with anchoring means behind the machine to exert a rearward stress on the main frame at a point nearer the outer end thereof than the said point of forward stress thereon, and means mounted on the main frame adapted in coöperation with the rear cable section to cause the inner end of the machine to swing forward and backward as the machine advances along the coal face.
- 20 28. In a mining machine, the combination of a main frame, a cutting apparatus projecting from the inner end thereof, cable guide devices mounted on the main frame, one of said guide devices being nearer the inner end of the machine than the other, a continuous cable engaging the guide devices on the machine and adapted to be extended forward to an anchor in front of the machine and rearward to an anchor behind the machine, a rotary means on the machine engaging the cable and adapted to create tension therein to advance the machine, and means mounted on the main frame for varying the course of the cable in relation to said frame and thereby varying the distance between the outer part of the main frame and the rear anchor.
- 25 29. In a mining machine of the class described, the combination with the main frame, cutting apparatus projecting inward therefrom, the motor and the gearing thereon all adapted for undercutting coal while moving on lines along the face of the coal, of a feed and guide mechanism comprising a cable-winding device on the frame, a continuous cable having a forward extending section connected with the cable-winding device to coöperate with anchoring means in front of the machine to exert a forward pulling stress on the main frame at a point near the inner end thereof and a rearward extending section adapted to coöperate with anchoring means behind the machine to exert a rearward stress on the main frame at a point nearer the outer end thereof than the said point of forward stress thereon, and manually controllable devices on the main frame adapted to vary in relation to the machine the lines along which the cable stresses are exerted thereon.
- 30 31. In testimony whereof I affix my signature, in presence of two witnesses.
